Primary Examiner — Anhdao Doan(74) *Attorney, Agent, or Firm* — S&P San Francisco, LLP;
Yue Xu(57) **CLAIM**

The ornamental design for a dividable microplate cover sheet, as shown and described.

DESCRIPTION

FIG. 1 is a top plan view of a dividable microplate cover sheet showing our new design;

FIG. 2 is a bottom plan view of the dividable microplate cover sheet;

FIG. 3 is a right side elevation view of the dividable microplate cover sheet. The left side elevation view is a mirror image thereof; and,

FIG. 4 is a front elevation view of the dividable microplate cover sheet. The rear elevation view is a mirror image thereof. The broken lines in the figures are tear lines and are part of the design.
